(57) **CLAIM**

The ornamental design for a accumulator charging apparatus, as shown and described.

DESCRIPTION

1. Accumulator charging apparatus

1.1 : Perspective

1.2 : Perspective, cover removed

1.3 : Front

1.4 : Left

1.5 : Back

1.6 : Top

1.7 : Perspective

1.8 : Right

1.9 : Perspective

1.10 : Bottom
